CLAIM

The ornamental design for a sequencing instrument as shown and described.

DESCRIPTION

1. Sequencing instrument

1.1 : Perspective

1.2 : Front

1.3 : Back

1.4 : Left

1.5 : Right

1.6 : Top

1.7 : Bottom

1.8 : Perspective

1.9 : Enlarged

The broken lines shown in the figures depict portions of the sequencing instrument that form no part of the claimed design; the dash-dot-dashed curved and straight lines and the

(Continued)

number “1.9” in Fig. 1.8 are for the purpose of depicting the cut line of the enlarged view and form no part of the claimed design.
